UNITED STATES PATENT OFFICE.

ALBERT A. MONTERO, OF SPRINGFIELD, MISSOURI, ASSIGNOR TO GASTON M. SERRANO, OF ST. LOUIS, MISSOURI.

ILLUMINATED TOOL HOLDER.

Application filed October 9, 1923. Serial No. 667,519.

To all whom it may concern:

Be it known that I, ALBERT A. MONTERO, a citizen of the United States, residing at Springfield, in the county of Greene and 5 State of Missouri, have invented certain new and useful Improvements in Illuminated Tool Holders, of which the following is a specification.

In carrying out the present invention, it 10 is my purpose to provide a tool holder for benches and the like that embodies a source of illumination, preferably a flash-light, for facilitating the placing and removal of said bolts and nuts in dark places.

15 The primary object of the invention is to provide an illuminated tool holder, wherein different forms of holders per se, may be employed for permitting the device to be used in conjunction with varying types of 20 tools, and wherein the source of illumination may be switched on and off in a novel, simple and expeditious manner by the operator.

A still further object is to provide such 25 a device that is extremely simple of construction, and that may be manufactured and marketed at small cost, and one that will embrace at the same time the desired features of efficiency and durability.

The nature and advantages of the invention 30 will be better understood when the following detailed description is read in connection with the accompanying drawing, the invention residing in the construction, combination, and arrangement of parts as 35 claimed.

In the drawing forming part of this application, like numerals of reference indicate similar parts in the several views, and wherein:

40 Figure 1 is a side elevation of my improved holder.

Figure 2 is a longitudinal cross section thereof.

Figure 3 is an elevation of the underside 45 of the holder element per se, and

Figure 4 is a fragmentary detail cross section of one end of a modified form of holder.

First, having reference to Figures 1 to 3 50 inclusive, my device includes a handle 5 of relatively elongated cylindrical shape, open at one end, and internally screw threaded as at 6. Adapted for screw threaded engagement within said screw threaded end of the cylindrical handle is the screw thread-

ed hollow extension 7 of a tool holder element designated generally 8. This extension 7 is of lesser cross section area than the said tool holder for providing a shoulder 9, that is adapted to bring up against the end 60 of the handle 5 for obvious purposes, as more clearly shown in Figures 1 and 2. This said holder 8 is in the form of a tube section having a cut-out portion 10 upon its underside, and formed with a cross strip 11 at its 65 front end for providing a socket 12 for the reception of the flat-like handles of wrenches or other tools.

The cylindrical handle 5 is adapted to receive a dry cell battery 13 formed at its 70 front end with the usual contact 14. In engagement with this contact is the usual contact 15 of an electric lamp (not shown) that is carried by the usual form of conical shell 16. This conical shell 16 carries a 75 bull's-eye lens 17, and has close contact at this end with a concaved shoulder 18 formed within said tool holder 8. The battery 13 together with the projector formed by the elements 16 and 17 is maintained in 80 the position shown in Figure 2 by an expansion spring 19 between the opposite end of the battery, and one end of a switch button 20, that has lateral movement within an opening 21 at the closed end of the cylindrical handle 5. The opposite ends of 85 this button 20 are insulated from the closed end of the member 5, through the medium of non-conducting disks 22.

In actual practice, the end of the wrench 90 handle or other tool being used is engaged within the socket 12 of the member 8 and a switch button 20 moved for contacting the shank thereof with the edge of the opening 21 in the closed end of the cylindrical handle 5, thereby completing the circuit to the bulb within the shell 16, whereby the bolt, nut or other article being operated upon, 95 will be fully illuminated.

In the modification, Figure 4, the cylindrical handle 5' is open at its end opposite from the end that carries the tool holder element, and is internally screw threaded. Positioned within this end of the handle 5' is a cap 23 that is formed with an opening 100 24, through which extends the shank of a switch button 25. Between the inner end of this button and the battery 13' is an expansion spring 19', and between the opposite ends of said button and the cap 23 are 105 110

insulating disks 26. In this instance, it will be at once understood that the battery 13' may be removed without necessarily removing the tool holder carried by the opposite end of the handle 5'.

- It is of course to be understood that different forms of holder elements per se, may be employed in conjunction with my device, and in view of the above description when 10 considered with the accompanying drawing, it will at once be apparent to those skilled in the art the numerous advantages of an article of this character, and even though I have herein set forth the practical embodiment of the invention, it is nevertheless 15 to be understood that minor changes may be made therein, without departing from the spirit and scope of the invention as claimed.
- 20 Having thus described my invention, what I claim as new, and desire to secure by Letters Patent, is:
1. An illuminated tool holder comprising a cylindrical hollow handle, open and internally screw threaded at its outer end, a 25 tool holding device having a substantially semi-circular socketed extension disposed in

alignment with said handle, said device being provided on its inner end with a reduced screw threaded nipple tapped into the 30 threaded end of the handle, that portion joining the nipple with the extension being provided with an internal shoulder adapted to be engaged by a flash light bulb and having an opening therein of the size 35 to permit simultaneous projection of light rays through and beneath said extension.

2. In an illuminated tool holder, a body including a substantially semi-circular socketed extension, the under side of which 40 is flat faced, said body being provided on its inner end with a reduced screw threaded nipple at the inner end of which is internal and external shoulders, the wall of that portion of the body joining the extension and 45 nipple being gradually increased in width from the extension to the nipple, said intermediate portion being hollow and the front wall thereof being opened to make for simultaneous passage of light rays which are 50 adapted to be projected therethrough.

In testimony whereof I affix my signature.

ALBERT A. MONTERO
